UNITED STATES PATENT OFFICE.

ROBERT STANLEY BROWN, OF LONDON, ENGLAND.

CLOSURE FOR BOTTLES, TINS, JARS, CONTAINERS, AND RECEPTACLES.

Application filed November 1, 1921. Serial No. 512,153.

To all whom it may concern:

Be it known that I, ROBERT STANLEY Brown, of London, England, a subject of the King of Great Britain and Ireland, have 5 invented certain new and useful Improvements in and Relating to Closures for Bottles, Tins, Jars, Containers, and Receptacles, of which the following is a specification.

Wherever I herein use or refer to any of 10 the four words:—lid, lids, lid's, lids', I refer to and include any and all herein (as well as now) mentioned or described caps, lids, capsules, covers and the like and any of their kinds.

15 Wherever I herein use or refer to any of the four words:—receptacle, receptacles, receptacle's, receptacles', I refer to and include any and all herein (as well as now) mentioned or described bottles, tins, jars, containers and receptacles and any of their kinds.

Wherever I herein use or refer to any of 20 the four words:—rim, rims, rim's, rims', I refer to and include any and all herein (as well as now) mentioned or described rims, dependent flanging, skirting, bands, or rim-like formations, and any of their kinds, whether integral or non-integral with a lid, used in any suitable lid retaining manner 25 in one piece or suitably joined pieces, or interruptedly formed.

Wherever I herein use or refer to any of 30 the four words:—Lock, locks, lock's, locks', I refer to and include any one (or any greater number) of any and all of the herein mentioned or described manners, forms, types, and classes of rim provisions and means whereby a rim engages a receptacle (or its attachment or attachments) to obtain 35 a secure or positive shouldering hold thereon.

Wherever I herein use or refer to any of 40 the four pairs of conjointly used words: Receptacle's grip, receptacle's grips, receptacle's grip's, receptacle's grips', I refer to and include any one (or greater number) of any and all of the herein described, or stated receptacle's portions or provisions for engaging the said lock or locks. All the above 45 definitions are intended to apply to the description of and all claims for, this inven-

tion excepting to that extent in which the context explicitly and clearly is incapable of admitting that I have such intentions.

This invention relates to improved means 55 for connecting the rims of lids to receptacles and comprises the following novel combination, namely, a receptacle provided with at least one exterior engaging grip constructed to effect its engagement in a shouldering 60 like manner at a substantially uniform engaging height with respect to the said receptacle's axis and a lid's rim inwardly deformed (after application to the said receptacle) at well separated space intervals 65 to form locks adapted to engagingly coact with the said receptacle's gripping provision, such locks having (below the level of their engagement) side supporting connection with a non-locking portion of the said rim, 70 said locks being so accessibly disposed with respect to said receptacle as to admit of said rim's removal without destruction of the non-locking portion of the rim, said rim being so constructed as to be sufficiently pliable 75 to readily re-distort outwards on inside pressure being applied to its locks.

In such manner I obtain a few points of locking hold, having only to outwardly reform one or at most but a few locks to 80 speedily remove even the largest closure, yet without the inherent lack of lock stability with respect to the rim's body usually existing in inwardly bent engaging rim's tongues, scallops, and the like. By the formation of the locks at the time stated I not only avoid all necessity to use screwing methods of application and so avoid the risk of the disturbance of annular sealing media, but I am able to comply with the other numerous special requirements incidental to preserving putrefactive goods and the rapid closing of receptacles; as well as to conform 85 to shapes of receptacle's grips most easily produced in sheet metal, and pressed and automatically made vitreous material and the like.

I shall hereafter refer to a few general forms of receptacle's grips, a few general forms of inwardly deformed locks, and a few 90 manners of locally strengthening the latter or the rim or the lid in general, or

weakening the same, most of which said forms and manners are clearly not novel, but on the contrary, obviously forms and manners which packers are well accustomed to and equipped to efficiently carry into effect with most numerous variations. Such lock and rim strengthening however when used is obviously limited to an amount to give strength without prejudice to the said pliability of the rim, otherwise the said intended rim freeing possibility would be frustrated. I am aware it has been proposed to employ incised and other indents in rims specially stiffened to have no such said pliability and on receptacles where the lock material was inaccessible to be re-deformed to its non-locking original state; as also to position locking lugs in plain portions of rim flanging the latter so stiffened and the lugs so inaccessibly positioned as to be unsuitable for my said manner of removal and moreover arranged in special combinations with roughened turning flanging. To all such construction I make no claim herein, nor to any kind of lock fully formed prior to application to its receptacle or of a character essentially entailing such prior formation; shapes of deformed indents hitherto employed being obviously most numerous.

30 The said side supporting non-locking portion of the rim I prefer to form to have bearing (substantially in the line of the locks) against the receptacle's external periphery to prevent the rim being sprung off and to thus generally stabilize the rim and its locks.

This invention relates to rims of innumerable shapings, being for example applicable to inkwells, pepperettes, holed lids (with or without hinging), in fact to any pliable closure rim formation or flanging capable of use with a receptacle shaped externally in the immediate vicinity of its orifice in accordance with the requirements apparent from this description, whether such vicinity be oval, round, rectangular, or other geometrical or irregular shape.

The rim or lid may be made of iron, tin-plate, brass, aluminium, electroplate, tagger sheet, or any other suitable material or materials.

Hereafter I use the following numbers as a reference to the features or conditions they indicate. This invention may be used for closures of (1) hermetic, (2) pressure resisting (3) hermetic vacuum (4) automatic vacuum, types; each with (5) such regulatable automatically re-seating safety valve action as is desired; and by this invention's 55 constructions and application method, excepting where I state otherwise, the foregoing five closures can:—

(6) fulfil their holding duties without damage or permanent displacement of locks,

(7) have sealing (and re-sealing) com-

pression applied and retained to any desired degree,

(8) be re-applied in the original, or a new, or more than one, "on" position on the receptacle, taking up "set" in sealing media 70 without requiring rotation,

(9) optionally entail destructible removal to prevent fraud,

(10) be optionally provided with auxiliary retaining means,

(11) be applied to most existing forms of receptacles,

(12) ensure less risk than heretofore of receptacle damage when applying despite their usual inaccuracies,

(13) be readily and speedily removed without special appliance,

(14) resist internal receptacle pressure to the actual shear or destruction strength of locks,

(15) be applied without turning the lid, thus preventing disturbance or injury of annular sealing media,

(16) resist transit disturbance,

(17) retain or prevent loss of sealing media when the lid is removed,

(18) have exceptionally liberal deformation of lock, with correspondingly increased hold and liability of obvious lock destruction in releasing,

(19) automatically tend to draw the locks inwards as the internal receptacle pressure rises,

(20) retain indefinitely cold pressures, and without structural alteration still release identical pressures under high internal temperatures,

(21) be made of less material than heretofore possible for these combined conditions,

(22) be applied rapidly with human power only and without having to rotationally register a lid to a receptacle,

(23) automatically adapt itself to the many processing methods used for foods, 110 and whether wholly or partially cooked in the receptacle after closing,

(24) in one form of construction and application meet all requirements above, as well as selected combinations thereof, under 115 which conditions the closure is generally characterized in that it is constructively proportioned as though the receptacle's internal pressure was a load and the lid or rim the load support, whose span (lock spacing), strength, and stiffness have been scientifically proportioned by static considerations and conditions to get a recoverable specific deflection of the lid or rim between the locks to obtain pressure 120 release under such load with due compensation for (and consideration of) the following factors (when present):—the extent to which the sealing medium is compressed to allow for receptacle inaccuracies 125 130

together with its initial and ultimate compression desired; temperatures' expansion effects; processing time, temperature, and method; the recoverable yield, spring, and 5 strength properties of the lock.

I use a receptacle which has in one or more suitable positions any indentations or 10 projections or shaping or provision which would obviously provide a receptacle grip for rim locks of the nature herein set forth, as, for example, grooving, flanging, beading, recessing, bosses, folds, seams, corrugations, false or full wiring, or combinations thereof, selected and shaped as suits the receptacle's construction or material.

The locks which engage with the receptacle's grips may be of any suitably disposed form of pushed in rim material the hereinstated deformation process could form, a 20 few, for example, being dentures, indents, cuts, slots, pips, in fact any configuration I choose to embody in the after stated incising and deformation tools, excluding as stated the few proprietary special combinations of 25 locks hereinbefore mentioned.

I may use any suitable sealing medium, media, or packing, in ring, laminated, disc or any other suitable form, shape, or cross section, whether loose, held by adhesion, 30 or any other suitable means, irrespective of position, and whether placed, folded, crimped, seamed, or applied in plastic or fluid or solid condition into any suitable grooving or any other suitable position in 35 (or on) the lid, rim, or the receptacle. For example I may use cork, fibre, paper, papier mâché, balata, though for most purposes I use dependably impervious material, such as rubber, rubber compositions, impregnated cork (or paper) and dispose sealing media between the lid or rim and the receptacle.

An example of application of the closure is as follows:—I first apply (mechanically 45 or by hand) the lid or rim to the receptacle as a freely fitting member, unprovided as yet with fully formed locks (though sometimes with partially formed locks or auxiliary engagements), said sealing media being in the sealing position. I next place 50 the receptacle on a floatably (or cushioned) supported table, directly beneath a fixed tool holding head provided with receptacle centering guides. By a spring governed foot lever, or any other suitable means, the 55 table is raised, the receptacle centering itself in the said guides and its lid or rim being brought up to meet the tool head truly flush, as receptacle inaccuracies are compensated for by said floating table, latter table being preferably leather faced. 60 The adjustment of the said spring (or the vertical traverse of the table) enables adjustment of the amount of compression of 65 the sealing medium. One or more pref-

erably mechanically constrained plungers attached to the said head now give to the rim's exterior surface, usually in a normal direction thereto, a blow or blows in such position that the rim's material at any suitable position is forced into some form of shouldering engagement with one or more of the receptacle's grips, thus forming locks. Said plungers may be blunt, or excising, or both, and so shaped at their tips 75 so as to form and inwardly deform rim metal as to make locks of the aforestated types.

I over compress the sealing medium beyond what I finally require, so that the 80 rim metal where forced inwards to form locks amply clears inaccurately positioned or formed receptacle's grips. This obviates damage to receptacles, and on the said table being lowered, by using resilient sealing 85 media, the latter forces the lid or rim to rise, the locks then bearing on the said grips. A bevelled underside of a receptacle's grip, if struck by a plunger, obviates receptacle breakage as the resultant vertical reaction 90 on the said underside only adds (by slight uplift of the receptacle), a little extra compression to a portion of the sealing media.

I may, of course, fulfil the functions of 95 the plungers by any other suitable mechanism, using for example well known forms of denture or cutting appliances of rotary action. It is clear that many hereinstated auxiliary engagements, rim, or lock, strengthening, and sealing media retaining 100 formations, may be simultaneously and similarly formed by the same plungers or subsidiary ones (or stated equivalent appliances) which make the locks.

By spacing the locks apart proportionate 105 to a rim's strength, or desirable amount of yield, (with due regard to temperature expansion effects in processing when necessary) or keeping the locks few in number, or by suitable combinations of these 110 features, I easily obtain in one closure above numbered features:—12, 13, 14, 18, 22, as well as 3, 4, 5, 6, 20, 23, the latter six features resulting by the ability of the lid or rim to materially (and recoverably) 115 yield between the locks, to further assist which yield I may locally strengthen (or as well as) weaken the lid, or rim, or rim's edge, (or all of these) by any suitable means, excluding as aforestated means of a proprietary character. For example localized weakening may result by my employing one or more suitably disposed cuts, slots, scallops, holes, or by strengthening where yield is not desired by one or more internal 120 or external bulges, internal and external projections, indentations, seams, folds, all which strengthening formations (or combinations of same) I may use as part of 125 the lock itself for strengthening same and 130

some forms assist the forming of locks, and suitably disposed other forms will obviously fulfil condition 17.

5 I may apply locks before or after processing, or both before and after to re-compress the seal, or to take up permanent set in same, by means of a rim's new on position.

10 The receptacle may be one having grips, or series of grips, disposed at varying levels (interrupted, continuous, or roughened, as desired) or also have suitably disposed protuberances to meet and force out the locks when the applied rim is turned. For 15 condition 8 or this new on position I may use a receptacle, or rim, or both, having respectively receptacle's grips or locks disposed at varying levels, or auxiliary engagements (optionally similarly disposed) of 20 any well known suitable type, for example:—snap-in, or snap-on, bosses or indents, pips, hooks, tongues, and the like, these suiting condition 10.

25 Receptacles or rims or lids may have in any suitable position or positions one or more:—recesses, indentations, projections, or any other suitable configurations serving as rim removing fulcra, additional rim or lid registers, retainers of sealing media, preventors of lateral rim play, guards against rim disturbance, and any other suitable provision of equivalent purpose.

30 The rim may be removed by forcing out the locks with a prong, or by any other suitable means for forcing the same outwards, or the lock provided with a wire or tongue to pull it outwards, said wire, or any other suitable means may retain lids or rims to receptacles to avoid their loss.

35 40 In closures (or even in the same closure) for condition 5, I may use locks unequally spaced and formed, some designed to permanently yield, others to recoverably yield, and for condition 9 somewhat brittle rim 45 metal may be used. I prefer cut locks (or slot locks) deformed respectively in towards, or on to, suitable receptacle's grip, as I obtain a metal shearing hold, which hold (properly spaced) suits all closure conditions I have numbered or set forth herein.

50 The lid and rim and receptacle are of any kind which is of a suitable shape or type to conform to the requirements and said characterization of the invention, which requirements are readily understood from the description and drawings here provided, it being obvious that many unstated innumerable combinations of my herein stated constructive features can be effected without departing from the spirit of this invention. I may, for example, suitably dispose and use my stated strengthening formations in innumerable ways and directions to give a general (or localized) strengthening to a 55 rim, or lid's top.

This invention permits of shallow rims, using little material, as a receptacle's bearing if very shallow provides a suitable grip, as it is subjected to less stresses than is customary for a closure of my properties. 70 I thereby save rim material, and receptacle cost. The invention may be used either to retain a stopper or non-hermetic closure.

75 Referring to the drawings filed here-with:—

Fig. 1 is a perspective view of a receptacle showing one form of closure made in accordance with this invention partly in section;

Fig. 2 is a perspective view of another form of closure;

Fig. 3 is an elevation of a circular closure;

Fig. 4 is a perspective view of a closure as applied to a rim band;

Fig. 5 is a perspective view of closure and receptacle embodying this invention.

In each of all of the attached figures, I show one of the many forms of closures in accordance with this invention. In these figures *a* is the receptacle, *b* the lid, *c* the rim, *d* strengthening formations for the rim or the lock, *e* the receptacle's top, *f* the receptacle's grips, *g* auxiliary receptacle grips, permitting of varying "on" positions for the rim or lid, *h* packing on the receptacle, *j* strengthening formations on the lid, *k* *k'* locks for engaging *f* or *g* on the receptacle, *l* a protuberance on the receptacle to co-act with the locks, forcing the latter out of locking position, when the lid *b* is turned, *m* *m'* weakening (or strengthening) formations which affect the rims' or lids' yielding tendency to facilitate or regulate safety valve action.

100 In all drawings, the locks are presumed to have been proportioned or spaced commensurate with the pressure of sealing, rim strength, and extent of lid or rim yield for condition 5.

105 In the perspective (partly sectioned) view shown in Fig. (1) is exemplified a form relating to all claims. The ample distance between *k* and *k'* permits of pre-determined yield of the lid in somewhat arched form between *n* and *o* when internal receptacle pressure reaches that which the closure is 110 designed to release. Such release would occur past the sealing medium *h* (in this case a ring of rectangular sectioned rubber) and between the positions *p* and *q*, and *o* and *n*. The position of the strengthening dishings *m'*, and the weakening formations *m* all help this effect, and locks formed on the corresponding rim sectors of *m'* are 115 particularly immune from disturbance. *d* in this case is an all round internal fold but uninterrupted at the scallop *m*, *m*. *j* tends to retain *h*. *r* is an indent, numbers of which may be placed on the rim (at several levels) to serve as light grips for 120 125 130

preliminary (or re-) application of the lid (in a new or more than one locked on position if desired), and any disposed between the weakening slots m are usually preferred, 5 rim metal here being more yielding. Along the line $o \dots s$ is a ridge caused by defective moulding. The upper face of the deforming tool t , should it encounter the track of this ridge on the receptacle's grip (in this 10 case the all round bead f) may cause a breakage of the receptacle, were it not for the fact that h permits the receptacle to probably avoid this at the expense of a little extra compression of h at the position 15 o , possible in virtue of the liberal lock spacing. I show this closure applied by means such as described herein, u being the floating table top, which on rising presents the top of b flush to the tool head x , intended 20 to abut (or register) on b 's top (and carry a plunger for deforming the rim, t). The locks k and k' are engagingly formed after applying b to e . This closure exemplifies all the numbered twenty four features. 25 Fig. 2 shows perspectively a form of the invention illustrating how proper selection and combination of the means herein described readily gives a closure innumerable properties I have stated. The outline 30 is made with one press operation in one piece, the rim having a series of buttresses (six being shown). It is presented to a compound cutter, which at one operation makes three parallel rows of cuts x , y and 35 z . The x row serves to weaken the rim to yield better as a light safety valve. The y and z rows enable a suitable plunger (or rotary tool) to later force inwards any rim metal below (or between) them to serve 40 as locks duly strengthened by the corrugations w , the rim therefore having two optional locking positions on a suitably disposed receptacle's grip. The bent in portions v may provide suitable register with 45 this grip to prevent side play of the rim. The buttresses act as anti-disturbance cushions during rough handling of the closure. This type exemplifies all the numbered twenty four features except 17, 19, 24 and 50 7, and allows of easy adjustment of lock spacing (its sealing medium being placed on the top, or top and side of a receptacle). This type may obviously work in conjunction with a like receptacle as shown in 55 Fig. 5.

Fig. 3 shows in elevation a circular cover of like utility as in Fig. 2 and adapted to work on a like receptacle. The locks comprise tongues such as n or o (or both) deformed inwards to engage suitably disposed receptacle flanging. The inclination p p' of the lock's engaging edge enables uniformity of pressure on the sealing media to occur with spring controlled plungers notwithstanding irregularities in the level of

this flanging. d is a fold. This type exemplifies all the twenty-four numbered features except 14, 17, 19 and 24. Tongues such as q , may be used to pull out the locks.

Fig. 4 shows perspectively the invention 70 in the form of a detachable tongue jointed rim having flanging p to retain in place any suitable receptacle's cover; its crescent lock having like sealing compression properties as the lock of Fig. 3, in addition to its lock 75 being to some extent recoverably yielding. This type exemplifies all the numbered twenty-four features, except 9, 17, 24, and 18 partially. The formation d makes the lock less liable to tear. q is an indent (vertical) for registering the rim with a suitable tool head's pip, so that plunger tools (if desired) need not strike the rim where it is joined. It may obviously work in conjunction with a like receptacle as shown in 80 Fig. 1.

Fig. 5 shows perspectively an extremely simple and effective form. h is seated on e , the latter optionally having V-shaped or any other suitable grooves. d is an all round internal fold (sometimes crimped or V formed with varying depth and strength and also optionally omitted or interrupted between the locks for better safety valve action of the lid). The lock here shown is 90 almost touching the throat o for register. The ridge n serves as a fulcrum for a prong to prise the locks outwards when desired. 95

The rim may be slotted in any suitable form as at y so that one or more plungers may act directly on any suitable upturned (internal as well as external) rim edge formations (for example d) to deform and open out the upturned form only to be the lock; this type being very strong and variable, specially suiting recoverably springy locks for features 4 and 5, or non-springy locks, and also household preserving without special appliances. This type exemplifies all the numbered twenty-four features 100 excepting feature 7 which may be got by suitable readjustment of the lock forming tools, and feature 17 by adding suitably disposed plunger indents to the rim. In Fig. 1 at k and k' and in Fig. 5 at y the inner upturned fold d at these locking situations tends to substantially either become less flat (that is to say, it opens out inwardly) or to remain unaltered in distance with respect to the outer opposite flanging on forming the lock, due partially to the acuteness 110 and flatness of the fold and the fact that this lock metal is not buckled against the receptacle's throat by the deforming tool. In Fig. 3 the locks will comprise inbent shaded portions such as r the fold d being well below the actual line of locking engagement. In Fig. 1 at k as at Fig. 5 at y the incision in the rim wall makes no engagement. 115

120

125

130

In all figures whether the locks are the edges of incisions or not it will be noted that in each case where lock strengthening has been resorted to, provision has been simultaneously made for the ready distortion of the rim back to that non-locking contour which it had prior to the lock formation, by maintaining the pliability of the rim, and for arranging for the initial de-forming act (and its material weakening consequences) to occur at the place where rim strengthening is present yet without materially impairing the strengthening of the rim in respect of resisting vertical strains.

What I claim and desire to secure by Letters Patent is:—

1. A closure combination comprising a receptacle provided with at least one exterior engaging grip constructed to effect its engagement in a shouldering like manner at a substantially uniform engaging height with respect to the said receptacle's axis and a lid's rim inwardly deformed (after application to the said receptacle) at well separated space intervals to form locks adapted to engagingly coact with the said receptacle's gripping provision, such locks having (below the level of their engagement) side supporting connection with a non-locking portion of the said rim, said locks being so accessibly disposed with respect to said receptacle as to admit of said rim's removal without destruction of the non-locking portion of the rim said rim being so constructed as to be sufficiently pliable to readily re-distort outwards on inside pressure being applied to its locks.
2. A closure combination comprising a receptacle provided with at least one exterior engaging grip constructed to effect its engagement in a shouldering like manner at a substantially uniform engaging height with respect to the said receptacle's axis and a lid's rim inwardly deformed (after application to the said receptacle) at well separated space intervals to form locks adapted to engagingly coact with the said receptacle's gripping provision, such locks having (below the level of their engagement) side supporting connection with a non-locking portion of the said rim, said locks being so accessibly disposed with respect to said receptacle as to admit of said rim's removal without destruction of the non-locking portion of the rim said rim being so constructed as to be sufficiently pliable to readily re-distort outwards on inside pressure being applied to its locks, said locks being initially formed a little below the said receptacle's engaging portion simultaneous with the "over" compression of a resilient packing within the closure beyond that compression which the position of the said locks is adapted to retain.
3. A closure combination comprising a re-

ceptacle provided with at least one exterior engaging grip constructed to effect its engagement in a shouldering like manner at a substantially uniform engaging height with respect to the said receptacle's axis and a lid's rim inwardly deformed (after application to the said receptacle) at well separated space intervals to form locks adapted to engagingly coact with the said receptacle's gripping provision, such locks having (below the level of their engagement) side supporting connection with a non-locking portion of the said rim, said locks being so accessibly disposed with respect to said receptacle as to admit of said rim's removal without destruction of the non-locking portion of the rim said rim being so constructed as to be sufficiently pliable to readily re-distort outwards on inside pressure being applied to its locks, a strengthening formation being provided in said rim below the line of engagement of the said rim's locks.

4. A closure combination comprising a receptacle provided with at least one exterior engaging grip constructed to effect its engagement in a shouldering like manner at a substantially uniform engaging height with respect to the said receptacle's axis and a lid's rim inwardly deformed (after application to the said receptacle) at well separated space intervals to form locks adapted to engagingly coact with the said receptacle's gripping provision, such locks having (below the level of their engagement) side supporting connection with a non-locking portion of the said rim, said locks being so accessibly disposed with respect to said receptacle as to admit of said rim's removal without destruction of the non-locking portion of the rim said rim being so constructed as to be sufficiently pliable to readily re-distort outwards on inside pressure being applied to its locks, said locks being initially formed a little below the said receptacle's engaging portion simultaneous with the "over" compression of a resilient packing within the closure beyond that compression which the position of the said locks is adapted to retain.
5. A closure combination comprising a receptacle provided with at least one exterior engaging grip constructed to effect its engagement in a shouldering like manner at a substantially uniform engaging height with respect to the said receptacle's axis and a lid's rim inwardly deformed (after application to the said receptacle) at well separated space intervals to form locks adapted to engagingly coact with the said receptacle's gripping provision, such locks having (below the level of their engagement) side supporting connection with a non-locking portion of the said rim, said locks being so accessibly disposed with respect to said re-

- ceptacle as to admit of said rim's removal without destruction of the non-locking portion of the rim said rim being so constructed as to be sufficiently pliable to readily redistort outwards on inside pressure being applied to its locks, said receptacle being provided with at least one excrescence adapted to push at least one lock out of action substantially in the rotary manner herein described. 6. A closure combination comprising a receptacle provided with at least one exterior engaging grip constructed to effect its engagement in a shouldering like manner at a substantially uniform engaging height with respect to the said receptacle's axis and a lid's rim inwardly deformed (after application to the said receptacle) at well separated space intervals to form locks adapted to engagingly coat with the said receptacle's gripping provision, such locks having (below the level of their engagement) side supporting connections with a non-locking portion of the said rim, said locks being so accessibly disposed with respect to said receptacle as to admit of said rim's removal without destruction of the non-locking portion of the rim said rim being so constructed as to be sufficiently pliable to readily re-distort outwards on inside pressure being applied to its locks, further characterized in that the said locks are partially (but not fully) formed before the said closure is applied to the said receptacle. 7. A closure combination comprising a receptacle provided with at least one exterior engaging grip constructed to effect its engagement in a shouldering like manner at a substantially uniform engaging height with respect to the said receptacle's axis and a lid's rim inwardly deformed (after application to the said receptacle) at well separated space intervals to form locks adapted to engagingly coat with the said receptacle's gripping provision, such locks having (below the level of their engagement) side supporting connection with a non-locking portion of the said rim, said locks being so accessibly disposed with respect to said receptacle as to admit of said rim's removal without destruction of the non-locking portion of the rim said rim being so constructed as to be sufficiently pliable to readily re-distort outwards on inside pressure being applied to its locks, at least one of this said combination's said engaging provisions being at least double provided and in that manner adapted to provide at least two definite and alternative axial variations of "on" position of the said rim with respect to the said receptacle. 8. A closure combination comprising a receptacle provided with at least one exterior engaging grip constructed to effect its engagement in a shouldering like manner at a substantially uniform engaging height with respect to the said receptacle's axis and a lid's rim inwardly deformed (after application to the said receptacle) at well separated space intervals to form locks adapted to engagingly coat with the said receptacle's gripping provision, such locks having (below the level of their engagement) side supporting connection with a non-locking portion of the said rim, said locks being so accessibly disposed with respect to said receptacle as to admit of said rim's removal without destruction of the non-locking portion of the rim said rim being so constructed as to be sufficiently pliable to readily re-distort outwards on inside pressure being applied to its locks together with the provision of auxiliary retaining means for the closure of any suitable kind. 9. A closure combination comprising a receptacle provided with at least one exterior engaging grip constructed to effect its engagement in a shouldering like manner at a substantially uniform engaging height with respect to the said receptacle's axis and a lid's rim inwardly deformed (after application to the said receptacle) at well separated space intervals to form locks adapted to engagingly coat with the said receptacle's gripping provision, such locks having (below the level of their engagement) side supporting connection with a non-locking portion of the said rim, said locks being so accessibly disposed with respect to said receptacle as to admit of said rim's removal without destruction of the non-locking portion of the rim said rim being so constructed as to be sufficiently pliable to readily re-distort outwards on inside pressure being applied to its locks, means being provided to frustrate the withdrawing of the closure other than by re-deforming the locks to an outward position, said means comprising a substantially all round exterior shouldering provided on the receptacle suitably positioned to foul or engage at least one of the said locks in all rotational positions of the said rim with respect to the said receptacle on the said withdrawal being attempted. 10. A closure combination comprising a receptacle provided with at least one exterior engaging grip constructed to effect its engagement in a shouldering like manner at a substantially uniform engaging height with respect to the said receptacle's axis and a lid's rim inwardly deformed (after application to the said receptacle) at well separated space intervals to form locks adapted to engagingly coat with the said receptacle's gripping provision, such locks having (below the level of their engagement) side supporting connection with a non-locking portion of the said rim, said locks being so accessibly disposed with respect to said receptacle as to admit of said rim's removal without destruction of the non-locking portion of the rim said rim being so constructed as to be sufficiently pliable to readily re-distort outwards on inside pressure being applied to its locks together with the provision of auxiliary retaining means for the closure of any suitable kind. 11. A closure combination comprising a receptacle provided with at least one exterior engaging grip constructed to effect its engagement in a shouldering like manner at a substantially uniform engaging height with respect to the said receptacle's axis and a lid's rim inwardly deformed (after application to the said receptacle) at well separated space intervals to form locks adapted to engagingly coat with the said receptacle's gripping provision, such locks having (below the level of their engagement) side supporting connection with a non-locking portion of the said rim, said locks being so accessibly disposed with respect to said receptacle as to admit of said rim's removal without destruction of the non-locking portion of the rim said rim being so constructed as to be sufficiently pliable to readily re-distort outwards on inside pressure being applied to its locks, further characterized in that the said locks are partially (but not fully) formed before the said closure is applied to the said receptacle.

tion of the rim said rim being so constructed as to be sufficiently pliable to readily re-distort outwards on inside pressure being applied to its locks, the said locks being deformed in formation sufficiently far inwards as to collectively make a hold with the said receptacle sufficiently positive to frustrate

the springing off of the closure without initially permanently re-deforming the formation of at least one lock.

10

In testimony whereof I have signed my name to this specification.

ROBERT STANLEY BROWN.
